J. Franklin Meyer, ATTORNEY

UNITED STATES PATENT OFFICE.

ALEXANDER KATZ, OF BROOKLYN, NEW YORK.

WINDOW BOX.

Application filed June 30, 1924. Serial No. 723,285.

To all whom it may concern:

Be it known that I, ALEXANDER KATZ, a citizen of the United States, and resident of Brooklyn, in the county of Kings and State of New York, have invented certain new and useful Improvements in Window Boxes, of which the following is a specification.

This invention is an improvement in window boxes, and with respect to its more specific features, to the type of box used for food refrigeration and the like.

Devices of the character in question are not usually on sale as completed articles of manufacture, made in stock sizes and capable of attachment by anyone with the tools usually found in the home. They are usually built on the spot to fit the particular window and are adapted for use with the one window only. Moreover, such devices are usually designed for the support or storage of one class of food products only, either such as are not liable to contamination from the atmosphere, and hence may be openly exposed, or such as must be protected. In the former instance, the device is usually an open shelf, while in the latter it is usually a box.

An object of the present invention is to provide a simple device of the character specified, complete in itself, and capable of quick and easy attachment to any window having a frame of the size for which the device is designed.

Another object is to provide a device constructed and arranged for the support of articles in containers or protected in themselves against contamination from the atmosphere and having also means to shield articles not in containers or so protected.

Another object is to provide a device which may be cheaply constructed and sold at a reasonable figure, and which when in place will offer a minimum of obstruction to light and air, with a maximum of protection for the contents.

With these and other objects in view, the invention consists in the construction and novel combination of parts fully described hereinafter, illustrated in the accompanying drawings, and pointed out in the claims appended hereto, it being understood that various changes in the form, proportion, size and minor details of construction, within the scope of the claims, may be resorted to

without departing from the spirit of the invention.

In the drawings:

Fig. 1 is a front view of the improved box. 60

Fig. 2 is a top plan view with the window frame in section.

Fig. 3 is a rear view of the box detached.

Fig. 4 is a section on line 4—4 of Fig. 1.

Fig. 5 is a detail view in section of the 65 connection between the open wire work and the base.

Fig. 6 is a similar view of a modified construction.

In the present embodiment of the invention, the improved box comprises a base, which as shown in Figs. 1 to 5, may be composed of a suitable board 1 of wood or the like, and a plate 2 of sheet metal on the upper face of the board, the edges of the 70 sheet being crimped or bent about the edges of the board, as indicated at 3, to hold the parts together. At each end of one side of the base an upstanding channel member 4 is provided, the channels of the members 80 facing away from the board, as shown in Fig. 3, and these members may be integral with the plate 2, or connected thereto in any suitable or desired manner, as for instance, by soldering, riveting, or otherwise. 85

The elements 1 and 2 are of such length, that the channel members 4 will be spaced apart a distance corresponding to the spacing of the stiles 5 of the window frame of the type with which the improved box is 90 designed to cooperate, and the channel members are of such dimensions as to width and depth of channel, as to receive the edge of the stile, as shown in Fig. 2, the side walls of each channel member engaging opposite faces of the stile. The channel members have openings 6 of a suitable number, and of a size to receive holding members, as for instance, screws 7, to connect the channel 95 members to the stile. When the channel members are fitted to the stiles, as shown in Figs. 1 and 2, and the screws 7, or other securing means, are in place, the platform or shelf constituted by the elements 1 and 2 is supported in a horizontal plane, with the inner edge thereof resting upon the sill 8 of the frame, and with the shelf extending perpendicularly from the plane of the frame.

Any suitable material may be used for 110

forming a retaining wall at the outer side and end edges of the platform, a preferred material being open wire work, such as is kept in stock, in stock sizes. A suitable length of this material, of a suitable width, is connected to the edge of the platform remote from the channel members and to the ends thereof. This material is usually composed of lapping wicket or U-shaped members 9, which are connected by horizontal wires 10, the legs of the wickets being vertical. Each leg of each wicket-shaped member is provided with an angular lug 11 at its free end, and these lugs are passed through openings in the plate 2 and into engagement with the material of the plate 1, as shown in Fig. 5. Staples 12 are driven into the edge of the base, one over each leg, to firmly connect the wire work to the base. With this construction the improved box is well adapted for the support of all articles, such as food products, which do not require protection from atmospheric contamination, as for instance those in containers, such as milk in bottles, or those which are protected in themselves, as for instance, eggs. It is often desirable, however, to have in connection with the box means to shield materials which are not in themselves protected from contamination, and which are not in containers, as for instance, meats, butter and the like. To provide for this, a casing is arranged at one end of the box, the said casing occupying about one-third of the superficial area of the box base.

The improved casing which is rectangular in cross section, and preferably square in horizontal cross section, is composed of sheet metal, and comprises a body 13 having one open side and a top 14, the bottom being formed by the base of the box. The top is flanged as shown, and riveted or otherwise secured to the body, and a door 15 is provided for closing the open side of the casing. The door has a bead 16 at its edge, which slides in a channel-shaped guide 17 formed on the adjacent edge of the top 14, and the lower end of the door has a tubular portion or sleeve member 18, which slidably engages a rod or wire 19 supported by the inner edge of the base.

One end of the wire 19 passes through registering openings in the side walls of the channel member 4 at the end of the box adjacent to the casing. The other end has a lateral lug 20, which passes through an opening in the plate 2 and engages the base. A staple 21 engages about the wire near the said end, and not only serves to prevent disengagement thereof, but also as a stop to limit the opening movement of the door, as shown in Fig. 3. The end of the rod 19 beyond the channel member 4 may be upset, or headed, to prevent disengagement thereof from the channel member. As shown

more particularly in Figs. 4 and 5, the lower edges of the walls of the body are lapped on the edges of the base or shelf, and are secured thereto by the staples which connect the legs of the wicket-shaped members 70 to the base. It is obvious that any other securing means might be used, and that the wall 9-10 might be omitted at the casing, if desired, the wall being completed by the front and end wall of the casing. In this instance the wire work 9-10 would be connected directly to the casing, instead of extending on to a connection with the channel member. 75

If preferred the element 1 may be omitted 80 from the base, the base being formed by a plate 22 corresponding to the plate 2 of Fig. 1. The edges of the plate are flanged, as shown at 23, and the free edges of the flanges are reinforced by a bent-over edge 85 24. With this construction of base, the wall of the casing indicated at 25, and the wire work 26, are connected to the flanges of the plate 22. In the present instance the connection is made by passing the angular end 90 27 of the legs of the wicket-shaped members through openings in the flange, and through registering openings in the casing wall at the casing, the extremities of the angular portions being bent laterally, as shown in Fig. 6, to hold the parts together.

Partitions or shelves may be arranged within the casing, if desired. In the present instance a single shelf 28 is arranged transversely of the casing, the said shelf 100 having depending flanges at its side edges, as shown, and the shelf is supported by angle pieces 29, riveted or otherwise secured to opposite side walls of the casing. The angle pieces are of such length, that when 105 the shelf is in place the flanges 30 will depend at the ends of the angle pieces, thus to limit lateral movement of the shelf in the casing. The shelf may be easily removed, merely by lifting it from the angle 110 pieces and drawing it forward.

For the purpose of ventilation, the door 15 is provided with ventilating openings 31, the said openings being arranged in a figure of regular outline, as shown, for the 115 sake of ornamentation.

The wall, which for convenience, is made of open mesh wire, may be made of foraminous material of any character, as for instance, lattice work, wire cloth, or the like, it being desirable that the wall be of a foraminous character to permit the free passage of light and air, thus to minimize the obstruction of the window as greatly as possible. 120 125

In closing the door, the inner edge thereof engages behind the adjacent channel member; and the lower inner corner is cut away, so that the tubular member 18 does not engage the channel member. 130

What is claimed as new is:

1. In a window box including a base of a length to extend from the outer face of one stile to that of the other of a selected window frame, channel members at the ends of the base for engaging the outer face and sides of the respective stiles, means to secure said members to the stiles, a casing on one end of the base adjacent to one attaching member and provided with a door at the inner edge of the base, the base forming the bottom of the casing.
- 10 2. In a window box including a base pro-

vided with means to attach it to a window frame with one edge thereof on the sill of the frame, a casing secured on one end of the base, a laterally slidable door for the casing on the side adjacent to the sill, and guides for the door in which it slides, one guide on the casing, and the other on the base.

Signed at New York in the county of New York and State of New York this 23rd day of June, A. D. 1924.

ALEXANDER KATZ.
